CAROUSEL FOR HOLDING COMPONENTS OF FLORAL ARRANGEMENTS

Harry Carpenter Robinson, Signal Mountain, Tenn., as-
signor to American Manufacturing Company, Chatta-
nooga, Tenn.

Filed May 6, 1968, Ser. No. 11,796

Term of patent 3½ years

Int. Cl. D6—01

U.S. Cl. D80—9

Fig. 1

Fig. 3

Fig. 4

FIGURE 1 is a perspective view of a carousel for holding components of floral arrangements showing my new design.

FIGURE 2 is an elevational view taken from one side thereof;

FIGURE 3 is a top plan view thereof;

FIGURE 4 is a bottom plan view thereof;

FIGURE 5 is a section taken on the line 5—5 of FIGURE 2;

FIGURE 6 is a section taken on the line 6—6 of FIGURE 2; and

FIGURE 7 is a section taken on the line 7—7 of FIGURE 1.

I claim:
The ornamental design for a carousel for holding components of floral arrangements, as shown.
